SHOULDER PAD

Marian Stehlik, New York, N. Y.

Application September 29, 1945, Serial No. 619,303

3 Claims. (Cl. 2-268)

1

It is the usual practice to attach shoulder pads to garments by stitching.

This practice not only requires the provision of a pair of pads for each garment, dress, or the like, but makes necessary for use with washable garments opening of said stitching for removal of the pads before laundering, etc.

To substitute separable fastening means such as snap fasteners or the like for said stitching is not possible in many cases, partly because the shape of some garments is unsuitable for the purpose, and partly because such fasteners would show through thin and delicate fabrics, etc.

It has already been proposed, therefore, to provide garments with pockets at the shoulders for reception of removable shoulder pads. This, however, necessitates the provision of two pockets on each garment and is uneconomical as a consequence.

Hence, a further proposal departs completely from attaching the shoulder pads to the outer garment itself and, instead, attaches the shoulder pads removably to the shoulder straps of an undergarment, brassière, slip or the like. For this purpose the pads have on their bottom side loops through which such shoulder straps are to be threaded.

Not only is this threading operation tedious and disappointing, but it is possible only with undergarments whose shoulder straps are detachable at least at one end.

All these disadvantages and drawbacks are avoided by the object of my invention, which is a shoulder pad constructed somewhat similar to a pocketbook, i. e. a casing enveloping the pad proper having a relatively long flap attached thereto, adapted to be folded back upon and releasably anchored to said casing so as to form a long channel for reception of a shoulder strap of a garment.

In a preferred form of the object of my invention at least two quickly operable anchoring means such as snap fasteners are provided, each consisting of two parts, one of which is attached to said casing, and the other of which is attached to said flap.

Because of the long flap the shoulder pad is held with considerable friction on the shoulder strap and, therefore, without the slightest danger of dislodgement.

Besides, the flap so to say forms with the casing a hinge which, because of the length of its axle, greatly facilitates the engagement of the snap fasteners in attaching the pad to a shoulder strap.

2

Further features and advantages of the object of my invention will become apparent from the following description in connection with the accompanying drawing in which:

5 Figure 1 is a perspective front view of a pair of the new shoulder pads attached to shoulder straps;

Figure 2 is a bottom plan view of the pad shown in Figure 1 with its flap partly closed;

10 Figure 3 is a bottom plan view of a modification;

Figure 4 a perspective back view of a pair of the new pads attached to shoulder straps.

The pad proper 4 (Figure 3) is enclosed in a 15 casing 5 made from fabric.

According to Figure 2 the casing is closed by stitching 6, whereas according to Figure 3 the casing has an opening or a slot along the line 7 so that the pad proper can be removed from 20 the casing.

Figure 3 shows the pad 4 partly removed from the casing 5.

In accordance with my invention a long flap 8 is attached to the casing along the edge 9 therefore giving to the object of the invention an appearance somewhat similar to a handbag or pocketbook.

At least two releasable and preferably quickly operable anchoring means are provided for securing the free end of the flap to the casing. The drawing shows three snap fasteners for that purpose. The female parts 10 of these fasteners e. g. are attached to the casing, and the male parts 11 to the flap.

35 30 For attaching the new pad to a shoulder strap 12, shown in dot-and-dash lines in Figure 2, the flap 8 is completely opened and is inserted under said strap with the fastener parts 11 facing upwards. Thereupon the pad with its casing 5 is pressed down i. e. folded back upon the flap whereby the male snap fastener parts 11 are engaged into the female parts 10 similar to the closing of a pocketbook as indicated in the upper part of Figure 2.

40 35 The considerable length of the hinge formed by the edge 9 facilitates very much the matching and engaging of the parts 10 and 11 and generally the closing operation.

45 40 The shoulder strap 12 which may be permanently attached at both ends to the garment (not shown) is sandwiched in the channel formed between the casing 5 and flap 8, and because of the thus obtained extended contact of the 55 strap with both these parts the pad is securely

held in position without danger of accidental dislodgements.

As a further safeguard in this respect the casing 5 is provided with an arm pit loop 14 through which the wearer puts her arm before attaching the pad to the strap 12. Additionally this loop securely prevents accidental opening of the flap 8.

Of course, instead of snap fasteners any other kind of anchoring means may be used.

What I claim is:

1. A shoulder pad, comprising, in combination, a pad proper, a casing enveloping said pad proper, and a relatively long flap attached to said casing and adapted to be folded back upon and releasably anchored to said casing so as to form a long case open at both ends for reception of a shoulder strap of a garment.

2. A shoulder pad as claimed in claim 1, comprising two quickly operable anchoring means, such as fasteners, attached to said casing substantially at the ends of said long flap.

3. A shoulder pad as claimed in claim 1 having in addition an arm-pit loop attached to its outward end.
